UNITED STATES PATENT OFFICE.

FREDERICK CHARLES THOMAS COLEBROOK, OF LONDON, ENGLAND.

ROTARY MOTOR, PUMP, AND THE LIKE.

Application filed June 23, 1921. Serial No. 479,875.

To all whom it may concern:

Be it known that FREDERICK CHARLES THOMAS COLEBROOK, of 70 Packington Street, Islington, London, N. 1, England (whose post-office address is 70 Packington Street, Islington, London, N. 1, England), has invented certain new and useful Improvements in Rotary Motors, Pumps, and the like, of which the following is a specification.

This invention relates to rotary motors, pumps and the like which are primarily intended for fluid power transmission, but are also applicable for other purposes, and has for its object to effect certain improvements in rotary motors or pumps of the crescent-shaped chamber type wherein the vanes or pistons are mounted to slide in radial guides in a drum eccentrically mounted in a cylindrical casing, said improvements being intended to provide a motor or pump of this character that shall be both variable in capacity and readily reversible.

According to this invention the cylinder or barrel surrounding the drum carrying the vanes or pistons and other adjuncts of the rotor and heretofore forming the casing of the pump, is mounted to slide in a fixed outer casing and provided with means whereby it can be displaced transversely to the axis of the drum from a position of maximum eccentricity to a concentric position, thereby varying the capacity from a maximum to zero or by a still further displacement in the same direction so altering the position of the working chamber with respect to the intake and delivery or exhaust, that the flow of the fluid is reversed. Suitable intake and discharge passages are formed on diametrically opposite sides of the barrel which in all positions of the barrel are in communication with intake and discharge connections on the outer casing. The fixed outer casing is closed at its ends by removable end covers, which also close the ends of the barrel and are formed with concentric bearings for the drum shaft, ball bearing pressure balanced thrust rings or collars being also provided between the ends of the drum and the casing covers.

The invention is hereinafter described with reference to the accompanying two sheets of illustrative drawings, in which similar letters of reference are employed to designate similar parts in the different views. 55

Fig. 1 is a sectional elevation of a pump constructed according to this invention.

Fig. 2 is a sectional elevation taken at right angles to Fig. 1.

Fig. 3 is an end elevation with the end cover and ball bearings removed.

Figs. 4 and 5 are isometric detail views of vanes or pistons illustrating means for partly pressure balancing the same.

Fig. 6 is an end view of the vane illustrated in Fig. 4, and

Fig. 7 is a perspective view of a sleeve which is interposed between the vanes or pistons and the casing.

Referring to the drawings the outer casing *a* enclosing the displaceable barrel *b* is cast with suitable feet *a'* by means of which the casing can be bolted to its baseplate, and with diametrically opposed bosses *a²*, *a³*, bored to form horizontal intake and discharge connections. Apertured end flanges *c* on the casing serve for the attachment by means of bolts *c'* of removable end covers *d*, formed with bearing bosses *d'*, for the shaft *e* which terminate at their outer ends in 70 stuffing boxes not shown. 71

Inside the casing *a* the part surrounding the intake and discharge openings therein is faced to form vertical plane surfaces *f* against which smooth faced flanges *b'*, *b²*, 85 formed on the intake and discharge passages *b³*, *b⁴*, in the barrel *b* are adapted to slide, a suitable packing being interposed if desired. The barrel *b* is suspended in the casing by a screw-threaded spindle *g* 90 screwed or otherwise secured in a boss *b⁵* in the top of the barrel and extending vertically through a screw threaded sleeve *g'* mounted to rotate in a sleeve *g²* screwed into a boss *g³* in the top of the casing, the sleeve *g'* being provided outside the casing with an operating hand wheel or handle *g⁴*. By rotating the sleeve *g'*, the spindle *g* and barrel *b* to which it is attached, can be moved vertically and easily adjusted. A cup- 100

leather or other packing g^5 is interposed between the spindle g and boss g^3 to prevent leakage.

On the shaft e is keyed the drum h formed with radial recesses or seatings i for the reception of the pistons or vanes j and also recessed at its ends to receive hardened floating rings or sleeves d^2 surrounding the drum shaft, and on which the vanes bear with their inner edges. Three pistons or vanes are shown in the form of construction illustrated but it will be evident that the number of vanes may vary. In the outer faces of the vanes j circular segmental recesses or seatings are formed for the reception of segmental packing members k .

As illustrated in Figs. 4 to 6 the portions of the vanes or pistons j which fit into the grooves in the drum are provided in their side faces with recesses j' and have transverse passages j^2 extending from opposite faces of the vanes and communicating with the recesses as shown in Figs. 4 and 6, or may be provided with grooves j^3 to connect the recesses with a space under the vanes as shown in Fig. 5. The object of the recesses and passages or grooves is to partly pressure-balance the vanes by admitting a portion of the working fluid to the groove which for the time being is on the suction side, and thereby to counteract to some extent, that part of the pressure on the working face which tends to force the vane against the side of its groove, thus avoiding excessive friction between the vane and the side of its groove opposed to the working pressure.

The rotary drum h with its vanes or pistons is enclosed within the barrel b , the vanes bearing with their inner edges against the floating rings or sleeves d^2 as aforesaid and with their outer packed faces against a sleeve l interposed between the vanes and barrel and adapted to take the outward thrust of the vanes, said sleeve being formed with capacious apertures or slots l' between its ends to allow of the free passage of the working fluid to and from the pockets between the pistons. Sleeve l which is clearly shown in Fig. 7, is connected with the drum h by loose radial arms m inserted in slots n , o , formed in the ends of the drum h and sleeve l respectively, the arms forming a positive driving connection between the drum and sleeve and being supported between the floating sleeves d^2 on the drum shaft and ball bearings p Fig. 2 arranged in recesses in the barrel. Between the ends of the drum and the casing covers pairs of thrust rings q , q' are interposed with balls between them, the balls of each bearing being arranged to roll on one of the rings when adjustment of the barrel is taking place. The inner ring q of each pair which lies against the ends of the drum is pres-

sure balanced by admitting a portion of the working fluid to its outer face through a passage r leading from the interior through an opening in the wall of the barrel fitted with a non-return ball valve s , the passage r terminating in the recess in which the ball bearing p is located, from whence the pressure fluid passes between the bearing rings and through a leak passage into the space between the thrust rings q , q' . In view of the reversibility of the apparatus two such valve controlled openings s are provided one in communication with the high and the other with the low pressure side.

In operation the drum h with its vanes or pistons j and the sleeve l rotate together in the barrel b and by actuating the spindle g the barrel b , together with the sleeve l can be displaced in the casing a relatively to the drum to reverse the motor or pump, or vary the capacity from the maximum to zero by varying the eccentricity of the chamber as described.

Having now particularly described and ascertained the nature of my said invention and in what manner the same is to be performed I declare that what I claim is:—

1. A device of the character described comprising a fixed outer casing having inlet and outlet passages, an inner cylinder vertically slidably mounted in the outer casing and having inlet and outlet passages registering with the passages of the outer casing, a rotary shaft extending through said casing and said cylinder, a rotor carried by said shaft within said cylinder, said cylinder being capable of being eccentrically disposed with relation to the rotor to form the working chamber, pairs of thrust rings arranged between the ends of the rotor and casing, the inner ring of each pair being pressure balanced by working fluid admitted to its outer face from the inner cylinder, and means for vertically adjusting the inner cylinder to vary the eccentricity of the inner cylinder in relation to the rotor and control rotation of the rotor.

2. A device of the character described comprising a fixed outer cylinder of cylindrical shape and having inlet and discharge passages, an inner cylinder mounted to slide in the fixed outer casing and having inlet and discharge passages registering with the inlet and discharge passages of the fixed outer casing, a shaft journaled concentrically in the outer cylindrical casing and extended through the inner cylinder, a rotor mounted on the shaft and enclosed in the inner cylinder, the inner cylinder being capable of being eccentrically disposed with relation to the rotor to form the working chamber, pairs of thrust rings arranged between the ends of the rotor and casing, the inner ring of each pair being pressure bal-

anced to admit a portion of the working fluid to its outer face through a valve controlled passage in the wall of the inner cylinder, vanes or pistons mounted to slide in the axis of the rotor to vary the eccentricity of the inner cylinder with relation to the rotor from a maximum to zero or to reverse 10 the apparatus.

5 radial guides in the rotor and means capable of being operated from outside the casing to displace the inner cylinder transversely of

In testimony whereof he has affixed his signature.

FREDERICK CHARLES THOMAS COLEBROOK.
